UNITED STATES PATENT OFFICE

169,812

COMBINED LUNCH BOX AND VACUUM BOTTLE UNIT

Paul Hellman, New York, N. Y.

Application March 26, 1952, Serial No. 19,057

Term of patent 7 years

(Cl. D58—2)

To all whom it may concern:

Be it known that Paul Hellman, a citizen of the United States of America, residing at New York, in the county of New York and State of New York, has invented a new, original, and ornamental Design for a Combined Lunch Box and Vacuum Bottle Unit, of which the following is a specification, reference being had to the accompanying drawing, forming part thereof.

Fig. 1 is a perspective view of a combined lunch box and vacuum bottle unit, showing my new design.

Fig. 2 is a perspective view thereof with the bottle removed from the bag.

The characteristic feature of my design resides in the color contrast between the top and bottom of the bag and the bottle, the top portion of the bag matching with the bottom portion of

the bottle, and the bottom portion of the bag matching with the top portion of the bottle.

I claim:

The ornamental design for a combined lunch box and vacuum bottle unit, as shown and described.

PAUL HELLMAN.
